UNITED STATES PATENT OFFICE.

AUGUST E. MOLL, OF OLATHE, KANSAS.

ROAD-DRAG.

1,260,242.

Specification of Letters Patent. Patented Mar. 19, 1918.

Application filed October 29, 1917. Serial No. 198,976.

To all whom it may concern:

Be it known that I, AUGUST E. MOLL, a citizen of the United States, residing at Olathe, in the county of Johnson and State 5 of Kansas, have invented new and useful Improvements in Road-Drags, of which the following is a specification.

This invention is an improved road drag for use in scraping, leveling and smoothing 10 the surface of a road and also for use as a snow plow and embodying a beam having reversely extended ends arranged at an angle to the intermediate portion to prevent the beam from being casually overturned 15 and also embodying draw-heads which are detachably connected to the ends of the beam and a draft bar or evener which is detachably connected to either of the draw-heads, so that the drag may be used with 20 either side of its beam foremost and so that the drag may also be used with either its smoothing or road working surface lowermost.

One object of the invention is to effect improvements in the construction of the beam. 25

Another object of the invention is to effect improvements in the construction of the draw-heads so that the latter may be readily detachably secured on the ends of the beam.

Another object is to effect improvements 30 in the construction of the draw-heads and the draw-bar or evener so that the draw-bar may be readily detachably secured to either of the draw-heads and without the necessity 35 of employing bolts or other like fastening devices.

Another object is to effect improvements 40 in the construction of the clevises used on the draw-bar and the double trees.

With the above and other objects in view 45 the invention consists in the construction, combination and arrangement of devices hereinafter described and claimed.

In the accompanying drawings:—

Figure 1 is a perspective view of a road drag constructed and arranged in accordance with my invention. 50

Fig. 2 is a detailed transverse sectional view of the same.

Fig. 3 is a detailed vertical longitudinal 50 sectional view of the same.

Fig. 4 is a detailed longitudinal horizontal sectional view of the same.

Fig. 5 is a detailed section of the beam.

Fig. 6 is a detailed plan of a modified 55 construction of the beam.

Fig. 7 is a detail perspective view of one of the draw-heads.

In the embodiment of my invention I provide a drag beam 1 which may be made of 60 iron, steel, of malleable metal or of wood shod with iron or of any other suitable metal. The beam comprises an intermediate portion 2 which when the drag is in use is arranged obliquely to the line of draft and 65 also comprises end portions 3 which extend in opposite directions, one forwardly and the other rearwardly from the intermediate portion and which are at an angle to said intermediate portion and nearly parallel 70 with each other. Said angularly related end portions prevent the beam from being casually overturned. The end portions of the beam may be bent or formed at an angle to the intermediate portion as at 4 or may be 75 curved with reference to the intermediate portion of the beam as at 5 in Fig. 6 of the drawings.

The beam is reversible end for end so that either side may be arranged foremost and is 80 channeled in its front and rear sides from end to end as at 7. The opposing sides of each channel converge toward the center of the beam to form beveled faces 8 and edges 85 9, 10. The beam is flat on one side from end to end as at 11 and its opposite side has its intermediate portion ridged as at 12 and beveled on opposite sides from the edges 10 to the ridge 12 as at 13. When the drag is used with the ridged side of the beam lowermost the beam will carry the dirt back to the center and cause the dirt and clods coming from the front portion of the drag to feed in under the drag and be thereby pulverized and pressed smooth. The channeled working faces on both the front and rear sides of the beam enable the latter to be reversed end for end as well as turned

with either side 11, 12 uppermost so as to definitely prolong the life of the beam and enable the same to be used for a long period of time.

5 A draw-head 14 is provided for each end of the beam and said draw-heads may be detachably secured to the end of the beam. Each draw-head has its front end pointed and oppositely beveled as at 15 to form a vertical cutting edge 16 and each lower head 10 is also provided with a pair of spaced rearwardly extending arms 17 which correspond cross-sectionally and are adapted to fit in the channels 7 of the ends of the beam and 15 on opposite sides of the web 18 of the beam between said channels. A set screw, clamping bolt or other like device 19 is provided for one of the arms 17 of each draw-head, to engage in an opening in the beam web 18 and thereby detachably secure the draw-heads in place. The draw-heads are reversible with reference to the ends of the beam so that the latter may be reversed at will and the draw-heads used always with the 20 same side uppermost. Each draw-head is provided on its upper side with an upwardly extending shoulder 20 near its front end and also has on its upper side a plate 21 which is secured on the said shoulder and extends 25 rearwardly above the draw-head for a suitable distance, each shoulder and plate 21 forming in effect a longitudinal slot 22 extending rearwardly from the front end of the draw-head and open at the rear and upper sides. Each end portion 3 of the beam is provided on its upper side with a draft plate 23 which is detachably secured thereon and in effect forms the bottom of a slot 22. The rear end of each draft plate is 30 formed with a draft hook 24.

The draft-bar or evener 25 is provided at one end with plates 26 on its upper and lower sides which plates are provided on the upper and lower sides of said draft-bar 45 with spaced flanges 27 the width of the space between which corresponds with the width of the draw-heads so that the said end of the draft-bar may be detachably connected to either one of the draw-heads by placing the same in the slot 22 of the draw-head with the flanges 27 arranged on opposite sides of the draw-head. The draft-bar extends inwardly from the front draw-head and is provided at its inner end with a draft chain 28 which may be engaged with the draft hook 24 of the plate 23 of the rearwardly extending end of the beam.

A pair of double trees 29 are provided each at the center with a clevis 30 which is 60 triangular in plan and is formed with side loops 31 and an intermediate loop 32. Swingle trees 33 are connected to the ends of the double trees. A clevis 34 secured on the cen-

tral portion of the draft-bar, is similar to the clevis 30 and has its side loops 35 connected by chains 36 to the inner side loops of the double tree clevises. The outer side loops of the double tree clevises are connected to the draft-bar by chains 37 at points near the ends of the draft-bar and the intermediate loops 33 of the double tree clevises are connected to the draft-bar by directly rearwardly leading chains 38.

It will be understood that the draft-plates 23 will be secured on the upper side of the 75 end portions of the beam and must be reversed when the beam is reversed.

The foremost draw-head acts somewhat like a plow. The drag may also be used as a snow plow or snow scraper to push snow 80 from the center of the road to the ditch at one side. Hence my drag when thus used as a snow plow makes a good road at once and prevents snow from melting on the road bed.

While I have herein shown and described 85 a preferred form of my invention I would have it understood that changes may be made in the form, proportion and construction of the several parts, without departing from the spirit of my invention and within 90 the scope of the appended claims.

Having thus described my invention, what I claim is:

1. A road drag of the class described comprising a beam having an obliquely arranged intermediate portion and forwardly and rearwardly extending end portions, in combination with a draw-head adapted to be detachably and reversibly secured to either end of the beam and a draft element connected to the draw-head.

2. A road drag of the class described comprising a beam having an obliquely arranged intermediate portion and forwardly and rearwardly extending end portions, in combination with a draw-head adapted to be detachably and reversibly secured to either end of the beam and a draft element connected to the draw-head, said draw-head having a longitudinal slot extending transversely, thereacross and open at the rear side and said draft element comprising a draft bar detachably fitted in said slot.

3. A road drag of the class described comprising a beam having an obliquely arranged intermediate portion and forwardly and rearwardly extending end portions, in combination with a draw-head adapted to be detachably and reversibly secured to either end of the beam, a draft bar arranged in advance of said obliquely arranged portion and having one end secured to the draw-head, and a chain connecting said draft bar to the rear portion of the beam.

4. A road drag of the class described comprising a beam having an obliquely arranged

portion and an end portion at an angle to said obliquely arranged portion, a draw-head detachably and reversibly secured to said end portion of the beam and provided 5 with a beveled front end.

5. In a road drag of the class described, a beam channeled in its front and rear sides and comprising an obliquely arranged inter-

mediate portion and forwardly and rearwardly extending end portions arranged at 10 an angle to said intermediate portion, said beam being reversible and flat on one side and ridged on the opposite side.

In testimony whereof I affix my signature.

AUGUST E. MOLL.

Copies of this patent may be obtained for five cents each, by addressing the "Commissioner of Patents, Washington, D. C."
